(57) **CLAIM**

I claim the ornamental design for a bib, as shown and described.

DESCRIPTION

FIG. 1 is a rear perspective view of bib, showing a first embodiment of my new design;

FIG. 2 is a front elevational view of FIG. 1;

FIG. 3 is a rear elevational view of FIG. 1;

FIG. 4 is a left-side elevational view of FIG. 1;

FIG. 5 is a right-side elevational view of FIG. 1;

FIG. 6 is a top plan view of FIG. 1, the bottom plan view being a mirror image thereof;

FIG. 7 is a rear perspective view of a second embodiment thereof;

FIG. 8 is a front elevational view of FIG. 7;

FIG. 9 is a rear elevational view of FIG. 7;

FIG. 10 is a left-side elevational view of FIG. 7, the right-side elevational view being a mirror image thereof;

FIG. 11 is a perspective view of a third embodiment thereof;

FIG. 12 is a front elevational view of FIG. 11; and,

FIG. 13 is a rear elevational view of FIG. 11.

The broken lines in the figures represent perforations, and are part of the claimed design. It is understood that the top and bottom plan views of all embodiments are identical, and the left and right side elevational views of the first and third embodiment are identical, respectively.
